UNITED STATES PATENT OFFICE

LUDWIC A. WILCZEK, OF NEW YORK, N. Y.

PUNCTURING APPARATUS

Application filed December 20, 1929. Serial No. 415,402.

This invention relates to the method and means for puncturing or perforating fabrics and other materials, and has for one of its objects the provision of means adapted to 5 perforate material of any desired width and thus overcome the deficiencies and limitations of the present day perforating machines which are limited to accommodate materials of substantially narrow widths.

10 Another object of the invention is to provide a device of the character referred to that will prevent the buckling of the material during the process of perforation.

A further object of the invention is to 15 provide a device of this character with a master die plate or matrix adapted to rest upon the material to be perforated, and means for pressing the said plate against the material when the perforating pins are withdrawn 20 from same after perforation, to prevent the said material from lifting up or buckling.

A still further object of the invention is to provide a device of the character referred to with a punch or pin holding or carrying 25 plate and means associated therewith to limit the downward movement of the said plate, the said means also being adapted to raise the plate to its normal position after the perforating action.

30 Still another object of the invention is to provide a device of this nature adapted to perforate any desired material at an angle thereto.

A still further object of the invention is to 35 provide a device of the nature referred to, adapted to form a raised portion around the perforations.

Another object is to produce a device of 40 the character described in which the maximum simplicity of construction and operation is secured.

Other objects and advantages will appear 45 as the nature of the improvements is better understood, the invention consisting substantially in the novel arrangement and co-relation of parts herein fully described, and illustrated in the accompanying drawings, wherein similar reference characters are used 50 to describe corresponding parts throughout the several views, and then finally pointed

out and specifically defined and indicated in the appended claims.

The disclosure made the basis of exemplifying the present inventive concept suggests a practical embodiment thereof, but the invention is not to be restricted to the exact details of this disclosure, and the latter, therefore, is to be understood from an illustrative, rather than a restrictive standpoint.

55 The inventive idea involved is capable of receiving a variety of mechanical expressions, one of which, for the purpose of illustration, is shown in the accompanying drawings, in which:—

60 Figure 1 is a side view in elevation partly in section of my improved perforating device.

Figure 2 is an end view thereof partly in section.

65 Figure 3 is an end view showing the arrangement of the beams and separating members.

Figure 4 is a plan view thereof with parts broken away.

70 Figure 5 is an end view partly in section of a modified form of my invention, and

75 Figure 6 is a detail view showing how the raised portion is formed.

80 Referring to the drawings in detail 10 and 11 indicate a pair of beam like members, the beam 10 being placed and secured in place beneath the flooring 12 of a room, and the beam 11 above the said flooring and spaced from the lower beam 10 by tubular separating members 13 near each end of the said beams.

85 The said beams are secured or tied together by means of bolts 14, and nuts 15, the said bolts passing through the beams 10 and 11, and through the tubular members 13.

90 In the present instance I have shown my invention as adapted for perforating screen sheets for talking movies. It will readily be understood that as such screens vary in size from a comparatively small or narrow sheet to a substantially wide sheet, the present day perforating machines which are limited to

95 perforating materials of thirty-six inches or thereabout are not adapted for perforating screen sheets which are ten or more feet wide.

100 To overcome this deficiency I have provided a structure comprising the upper and lower

beams 10 and 11 in which the innermost tubular members 13 may be spaced apart a distance sufficient to permit a very wide screen sheet 18 to pass therebetween. A pad 19 made of felt 5 or any other suitable material is placed on the floor beneath the screen sheet in the area where the perforating operation is performed.

On top of the screen sheet 18 I place a 10 perforating device which comprises a die plate or matrix 20 which is provided with a plurality of holes or openings 21 throughout substantially the entire length and width thereof. Screw threaded studs or posts 22 are 15 secured to the said matrix plate at or near the four corners thereof and act as guides for a plate 23 containing headed piercing or perforating pins 24, there being one such pin for every opening in the plate 20. These pins 20 24 normally extend partway into the plate 20. A cover plate 25 secured to the pin containing plate 23 prevent the pins 24 from riding out of the said plate 23 during the piercing operation. A pair of bolts or screws 26 are 25 threaded through the plates 23 and 25 and are provided with thumb pieces or heads 27 and with nuts 28.

The operation of the device is as follows: A strip of material 18 of any desired width 30 and length is passed between the innermost tubular member 13 and located so that it covers at least the entire width of the member 10. The perforating device is then placed on the sheet 18 near one side edge thereof and 35 a pair of pressure exerting jacks are placed on the device, between the top or cover plate 25 and the under surface of the top beam 11, the jacks 29 are then operated to press the pin plate down to pierce the sheet. The lower 40 ends of the screws or studs 26 limit the downward movement of the pin carrying plate and nuts 30 on the corner studs 22 limit the uppermost position of the said plate. After the holes are pierced the jacks are removed 45 and the screws 26 are screwed against the matrix plate 20 to raise the pin carrying plate and withdraw the pins from the screen, at the same time holding the said matrix against the screen sheet and prevent the buckling there- 50 of when the pins are withdrawn. Springs 31 assist in raising the pin carrying plate to its upper position. The operation is then completed through the entire width of the material, after which the new area of such material is drawn through to present a new surface to be operated upon.

It will be noted that due to the fact that I employ pointed pins for perforating, no material is cut away from the screen sheet, but 55 where the pins penetrate the screen, the material will be forced down into the felt pad 19 and produce semi-spherical cup like projections 32 (see Fig. 6).

In Figure 5 I have shown a modified form 60 of my invention wherein I employ an inclined

or wedge like base 35 upon which I place the felt pad 19. In this form of my invention the openings 21 in the matrix are drilled at an angle to the surface of the said plate and the pins 24 are at the same angle in the nail carrying plate 23, thus when the pins are pressed through the screen material, the openings and cup like projections will be at an angle to the screen material. This I consider very important as in this way I am enabled to provide a screen sheet for talking movies which will permit the maximum amount of sound to pass through the screen with the minimum amount of loss of light and projection surface. 70 75 80

From the foregoing it will be seen that I have provided means for perforating materials of very large width, the perforations passing either vertically or angularly through the material, the said perforated material being provided with cup shaped projections at each perforation. 85

Having described my invention, what I claim as new and desire to secure by Letters Patent is:— 90

1. In a perforating device of the nature described, a perforated die plate, extending posts secured thereto, a second plate slidably mounted on the said posts, piercing pins in the second plate normally extending partway into the perforations of the die plate, a cover plate on the second mentioned plate overlying the piercing pins, and a pair of screws threaded into the pin carrying plate adapted to limit the downward movement of the said plate and also to raise the said plate by screwing same against the die plate after the piercing operation is performed. 95 100

2. In a perforating device of the nature described, an upper and lower pressure resisting member, a collapsible piercing mechanism supported on the lower pressure resisting member, the said piercing mechanism comprising a perforated dieplate, posts secured thereto, a second plate slidably mounted on the said posts, piercing pins in the second mentioned plate in operative relation to the perforations in the dieplate, a coverplate overlying the piercing pins, a pair of screws carried by the pin carrying plate adapted to limit the downward movement of the said plate and also to raise the said plate by screwing same against the dieplate after the piercing operation is performed, and pressure means adapted to be inserted between the upper pressure resisting member and the piercing mechanism. 110 115 120

In testimony whereof I hereunto affix my signature. 125

LUDWIC A. WILCZEK.
